(57) **CLAIM**

The ornamental design for a radio receiver with remote control, as shown and described.

DESCRIPTION

FIG. 1 is a front perspective view of a radio receiver with remote control, embodying my new design, with the antenna and back support piece shown in a closed position;

FIG. 2 is a front view thereof;

FIG. 3 is a back view thereof;

FIG. 4 is a top plan view thereof;

FIG. 5 is a bottom plan view thereof;

FIG. 6 is a side view thereof;

FIG. 7 is an opposite side view thereof;

FIG. 8 is an alternate condition front perspective view thereof, with the remote control detached from the radio receiver;

FIG. 9 is a front view thereof;

FIG. 10 is an alternate front perspective view with the remote is attached to the radio receiver and the antenna is in an open position; and,

FIG. 11 is an alternate back perspective view thereof, in which the back support piece is in an open position.
